TOY TRAIN CONTROLLER

Joseph L. Bonanno, Madison, N. J., assignor to
The Lionel Corporation, New York, N. Y., a cor-
poration of New York

Application July 6, 1949, Serial No. 3,736

Term of patent 14 years

(Cl. D26—1)

To all whom it may concern:

Be it known that I, Joseph L. Bonanno, a citizen of the United States of America, and a resident of Madison, in the county of Morris and State of New Jersey, have invented a new, original, and ornamental Design for a Toy Train Controller, of which the following is a specification, reference being had to the accompanying drawing, forming a part thereof.

In this drawing the single figure is a perspective view of a toy train controller, showing my new design.

The rear of the body portion thereof is the same as the front.

I claim:

The ornamental design for a toy train controller, as shown and described.

JOSEPH L. BONANNO.
